UNITED STATES PATENT OFFICE

2,478,582

SLIDING WINDOW SASH HOLDER

Lester W. Hughes, Newport, R. I.

Application November 7, 1945, Serial No. 627,212

2 Claims. (Cl. 292—75)

1

The present invention relates to new and useful improvements in window frames and sash therefor, and has for its primary object to provide a sliding sash and frame construction without embodying the use of sash weights, pulleys and sash cords, and at the same time providing means for holding the sash in a desired vertically adjusted position in the frame.

A still further object of the invention is to provide anti-rattling means for a sliding sash construction.

Another object is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part thereof, wherein like numerals refer to like parts throughout, and in which:

Figure 1 is a fragmentary view partly in side elevation and partly in vertical section of a sliding sash and frame constructed in accordance with the present invention.

Figure 2 is a horizontal sectional view taken substantially on a line 2—2 of Figure 1.

Figure 3 is an enlarged fragmentary vertical sectional view showing the locking dog for securing the sash in vertically adjusted position.

Figure 4 is a vertical sectional view taken substantially on a line 4—4 of Figure 3, and showing the locking dog in open position.

Figure 5 is a similar view showing the locking dog in closed position.

Figure 6 is a view in elevation of the keeper for the locking dog recessed in the window frame.

Figure 7 is an end elevational view thereof.

Figure 8 is an end elevational view of one of the bushings for the shaft for actuating the locking dog.

Figure 9 is a sectional view thereof taken on a line 9—9 of Figure 8.

Figure 10 is a side elevational view of the channel member mounted on the edge of the sash.

Figure 11 is an end elevational view thereof.

Figure 12 is a top plan view of the plug inserted in the upper end of the channel member.

Figure 13 is a side elevational view thereof.

Figure 14 is a bottom plan view of the plug threaded in the lower end of the channel member.

Figure 15 is a side elevational view thereof.

Figure 16 is a side elevational view of a modified form of channel member.

Figure 17 is an end elevational view thereof, and Figure 18 is a fragmentary view in elevation of the lower end channel member.

Referring now to the drawings in detail wherein for the purpose of illustration I have disclosed a preferred embodiment of the invention, the numeral 5 designates a window frame generally, while the numeral 6 designates the sash slidably mounted therein, the frame and sash being constructed of any suitable material, such as plastics, or the like, and of any desired color.

The inner edge of the sash 6 is recessed as indicated at 7 for receiving a molding 8 secured to the sash by screws or the like 9 and arranged with one edge of the molding engaging an edge of the windowpane 10 for securing the latter in position in the sash, the use of the molding thus eliminating the use of putty for securing the pane in the sash.

A channel member 11 which may be of dovetail formation in cross section as illustrated in Figures 1 and 2 of the drawings, or of tubular formation as indicated at 12 in Figures 16 and 17 of the drawing, is recessed in the side edges of the sash 6, the side edges of the channel member being formed with attaching flanges 13.

A plurality of balls 14 are positioned in the channel member 11 and placed under pressure by the influence of a coil spring 15 positioned in the upper portion of the channel with the lower end of the spring bearing against a block 16 engaging the uppermost balls and with the upper end of the spring surrounding a stud 17 projecting from the lower end of a plug 18 threaded in the upper end of the channel member. A threaded plug 19 also closes the lower end of the channel member.

The lowermost ball 14 rests upon the upper edge of a locking dog 20 which is pivotally mounted at its upper edge on a pin 21 extending transversely of the channel member 11.

The lower edge of the dog at its outer surface is formed with a pair of spaced apart lugs 22 adapted for engagement in horizontal slots 23 arranged in vertically spaced apart relation at the opposite edges of a vertical slot.

The dog 20 normally gravitates to a substantially perpendicular position as illustrated in Figure 4 of the drawings with the lugs 22 out of engagement with the notches or slots 23 and is swung outwardly with respect to the side edge of the sash for engaging the lugs in the notches by means of a cam formation 26 of rectangular shape in cross section formed intermediate the

ends of the shaft 26 having its ends journalled in bushings 27 recessed in the inner and outer surfaces of the sash 6. The end of the shaft 26 at the inner end of the sash is provided with the manipulating handle 28. The cam formation 26' on the shaft is engaged in a recess 29 formed in the rear surface of the locking dog 20 and upon a quarter turn of the shaft 26, one of the narrow edges of the cam formation 26' will be moved into position against the rear edge of the locking dog 20 to thus swing the dog outwardly to engage the lugs 22 in the notches 23 as illustrated in Figure 5 of the drawings whereby to lock the sash against movement.

An anti-rattling guide designated generally at 30 is provided for the sash, the guide being of T-shaped construction in cross section and is positioned in the channel member 25 of the frame and includes a vertical rib 31 on its outer surface positioned in the slots 24 of the channel member 25 to bear against the ball 14. The guide is secured against vertical movement in the channel member 25 by means of screws 32 employed for securing the guide to the frame 5, the heads of the screws engaging the upper and lower ends of the guide 30, as will be apparent from an inspection of Figure 13 of the drawings.

The guide 30 is projected outwardly through the slots 24 for engaging the balls 14 by means of coil springs 33 recessed in the rear edge of the guide and in the frame 5.

Both edges of the sash 6 and the inner edges of the frame 5 are provided with channel members 11 and 25 to hold the balls 14 and guide 30, respectively, to facilitate the free sliding movement of the sash in the frame and preferably only one of the locking dogs 20 and its associated parts are provided at the one side of the sash, as illustrated in the drawings.

Accordingly, in the operation of the device it will be apparent that the sash 6 is free to slide vertically in the frame 5 when the locking dog 20 is positioned substantially perpendicularly as illustrated in Figure 4 of the drawings and when it is desired to lock the sash in a vertically adjusted position, the handle 28 is manipulated to partially rotate the shaft 26 which thereby causes the cam formation 26' to swing the dog 20 outwardly toward the sash for engaging the lugs 22 in one of the notches 23.

In order to accommodate the outwardly swinging movement of the locking dog 20, the lower portion of the channel member 11 is cut away as indicated at 34 in Figure 18 of the drawings.

In view of the foregoing description taken in conjunction with the accompanying drawings it is believed that a clear understanding of the construction, operation and advantages of the de-

vice will be quite apparent to those skilled in the art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

10 I claim:

15 1. A sash balance for a sash slidably mounted in a window frame comprising a vertically extending channel member in an edge of the sash, a plurality of balls stacked in said channel member, a channel member in the frame, and a spring projected bar positioned in said last named channel member and having an edge engaging said balls, the channel member first mentioned extending to the top of said sash and having an open upper end at said top for insertion of said balls downwardly therein, a removable closure in said upper end of said first mentioned channel member for preventing the escape of said balls out of said upper end, and spring means in said 20 upper end between said closure and stack for yieldingly restraining the balls against vertical separation in the stack.

25 2. A sash balance for a sash slidably mounted in a window frame comprising a vertically extending channel member in an edge of the sash, a plurality of balls stacked in said channel member, a channel member in the frame, a spring projected bar positioned in the channel member of the frame and having an edge engaging said balls, the channel member first mentioned extending to the top of said sash and having an open upper end at said top for insertion of said balls downwardly therein, and a removable closure in said upper end of said first mentioned channel member for preventing the escape of said balls out of said upper end, said first mentioned channel member having relatively converging sides for confining the balls therein against escape out of the same laterally.

45 LESTER W. HUGHES.
